UNITED STATES PATENT OFFICE.

CHARLES MYRON JONES, OF NORTH YAKIMA, WASHINGTON.

LIFTING-JACK.

1,298,959.

Specification of Letters Patent. Patented Apr. 1, 1919.

Application filed April 1, 1918. Serial No. 226,036.

To all whom it may concern:

Be it known that I, CHARLES M. JONES, a citizen of the United States, residing at North Yakima, in the county of Yakima 5 and State of Washington, have invented certain new and useful Improvements in Lifting-Jacks; and I do declare the following to be a full, clear, and exact description of the invention, such as will enable others skilled in the art to which it appertains to 10 make and use the same.

This invention relates to lifting jacks, and it relates more particularly to an improved electrically operated jack.

15 The main object of this invention is to provide a jack that can be placed and operated from a point distant from the jack, principally to avoid the necessity of an automobile driver getting under the automobile 20 when necessary to jack up the same;

Another object is to provide an electrically operated device which is quickly and easily adjustable to either raise or lower the object supported thereby;

25 Another object is to provide an electrically operated lifting jack with an automatic make-and-break controlled by a reciprocatory movement of one of the elements thereof;

30 Another object is to provide a lifting jack of this character which is comparatively light, compact, strong and durable;

Another object is to provide a device of 35 this character which is composed of few and simple parts, so that it can be made at the minimum expense;

Other objects and advantages may become apparent to persons who read the following details of description in connection 40 with the accompanying drawing in which:

Figure 1 is a side elevation of the jack, its electrical connection and the pawl or handle whereby it is placed in its operative position.

45 Fig. 2 is a view observed at right angles to Fig. 1 showing the device partially in sections and partially in full elevation.

Fig. 3 is a view of a portion of the device, illustrating the pawl member in a position opposite to that in which it is shown 50 in Fig. 1; and

Fig. 4 is a horizontal sectional view taken along the line 4—4 of Fig. 1.

Referring to these drawings in detail, 55 in which similar reference characters correspond with similar parts throughout the

several views, the jack comprises a body or standard 5, a lifting member 6, bevel gear wheels 7 and 8, a toothed wheel or ratchet wheel 9, an actuating device 10, an operating device 11 and a base 12.

The standard 5 is provided with a vertical bore 13 which receives a screw-threaded element of the lifting member 6. The gear wheel 7 is provided with internal screw- 65 threads which mesh with the threads of member 6, so that when the wheel 7 is rotated the member 6 is raised or lowered in accordance with the direction of rotation of this wheel. The standard 5 is provided 70 with a supporting stud 14 on which the gear wheel 8 is mounted to rotate, and this wheel meshes with the wheel 7 and is integral or in fixed relation with the wheel 9.

75 The operating device 10 comprises a bar 15 of suitable material to constitute an armature or solenoid core, this member being preferably non-cylindrical throughout its length, and being supported and guided by bearings 16 which are supported by the 80 standard 5. The solenoid 11 is supported by the bearings 16 and is axially parallel with the standard 5, so that the member 15 is also axially parallel with the standard 5 and non-rotatable with relation thereto. 85 The upper end of the member 15 is slotted to receive a double pawl member 17 which is provided with hooks or shoulders 18 and is pivotally connected at 19 to the member 15. By causing the members 10 and 17 to 90 reciprocate vertically, the wheels 7, 8 and 9 are rotated by the engagement of one of the shoulders 18 with the teeth of the wheel 9.

95 In order that either of the shoulders 18 may be engaged with the wheel 9, so as to effect upward or downward movement of the lifting member 6, I may provide any appropriate form of reversing members, and one form will now be described as follows:

100 The member 17 is provided with a plate or projecting element 20, and to the lower end of this plate is pivotally mounted a link 21. The upper end of this link is provided with oppositely extending studs 22 and 23, the 105 former projecting between the oppositely extending arms of the member 17 and being adapted to rest alternately on these arms. To the stud 23 is connected a spring 24 which has its lower end connected to the upper bearing 16 and constantly pulls the upper end of the link 21 downward so as to

hold it in either of its alternative positions with relation to the pawl 17.

A helical spring 25 surrounds the upper portion of the member 15 and tends constantly to press the actuating device upward in opposition to a downward pull which is exerted by the solenoid 11 when the latter is energized. However, when the solenoid is deenergized, the spring 25 presses the actuating member upward so that it engages with a tooth of the wheel 9, and when the solenoid is energized it pulls the actuating device downward and thereby effects a partial rotation of wheel 9; and by repeatedly moving thus upward and downward, the lifting member 6 is either raised or lowered, according to which end of the shoulders 18 is in its operative position.

In order to energize the solenoid 11, I provide an electric conductor 26 provided with suitable connections 27, whereby it may be attached to the electric supply system of an automobile or other source; a manually operated switch 28, which may be of the push button type, as indicated in the drawings; and an automatically operated switch such as illustrated at 29, 30 and 31. The automatically operated switch comprises the contact 29 and lever 30 which is pivotally mounted at 31. The upper and lower ends of lever 30 are provided with cams 32 and 33 respectively, these cams being movable alternately into the path of the element 34 on the lower end of member 15.

By means of this automatically operated switch, the circuit is alternately closed and opened each time the actuating device moves up and down.

In order that this jack may be quickly, easily and conveniently placed under an automobile or other object to be raised, I provide the standard 5 with a socket 35 into which a pawl or handle 36 may be inserted. This handle member also being provided with an eye 37 which may be engaged with the stud 23 for shifting the link 21 from one to the other of its operative positions.

From the foregoing, it will be seen that I have provided for conveniently placing and operating a jack from a point distant from the jack, and the operation will now be described as follows:

Having first attached the handle 36 and thereby placed the jack in its operative position, the connection 27 may now be engaged with a source of electromotive force, and the switch 28 is now operated to close a circuit, it being understood that the parts are in the position shown in Fig. 3, the automatic switch being closed. The current passing through the solenoid 11 energizes the same, and the solenoid draws the member 15 downward until the element 34 strikes the element 33 and thereby opens the switch. This deenergizes the solenoid, so that the

spring 25 is allowed to raise the element 15 and its adjuncts. As the element 34 reaches its upward position it strikes the cam 32 and closes the automatic switch, thereby again energizing the solenoid. This operation is repeated so long as the switch 28 is held closed; but the raising operation immediately ceases upon releasing the switch 28 and allowing it to open the circuit.

When it is desired to lower the object which has been raised, the eye 37 is placed over the stud 23, and the rod or handle is pushed or pulled so as to cause it to reverse the position of the pawl 17, and the switch 28 is again closed so as to cause the member 15 to reciprocate as described in the foregoing. However, this reciprocation of the operating device rotates the wheels 7, 8 and 9 in the reverse direction from that previously disclosed, and the lifting member 6 now moves downward so long as the switch 28 is closed.

Although I have described this embodiment of my invention very minutely, it is not intended to limit my invention to these exact details of construction and arrangement of parts, but I am entitled to make such minor changes that are within the scope of the appended claims.

What I claim as my invention is:

1. An electrically operated jack comprising a standard, a vertically movable lifting element, mechanism supported by the standard for raising said lifting element, a reciprocatory device operable to actuate said mechanism, means for moving said reciprocatory device in one direction; an electro-magnet for moving said reciprocating device in the opposite direction, an electric conductor adapted to be in and out of circuit with said electro-magnet, and a switch adapted to be opened and closed and to throw said conductor in and out of circuit with said electro-magnet, whereby said means moves said reciprocatory device when the same has been freed from its control by said electro-magnet.

2. An electrically operated jack comprising a standard, a vertically movable lifting element, mechanism supported by the standard for raising said lifting element, a reciprocatory device operable to actuate said mechanism, means for moving said reciprocatory device in one direction; an electro-magnet for moving said reciprocating device in the opposite direction, an electric conductor adapted to be in and out of circuit with said electro-magnet, and a switch adapted to be opened and closed by movement of said reciprocating device and to throw said conductor in and out of circuit with said electro-magnet, whereby said means moves said reciprocating device when the same has been freed from its control by said electro-magnet.

3. An electrically operated jack comprising a standard, a vertically movable lifting element, mechanism supported by the standard for raising said lifting element, a reciprocatory device operable to actuate said mechanism; a magnet operable to move said reciprocatory device in one direction, automatic means to move said device in the opposite direction, and means controllable by movement of said reciprocatory device to alternately energize and deenergize said magnet.

4. An electrically operated jack comprising a standard, a vertically movable lifting element, mechanism supported by the stand-

ard for raising said lifting element, a reciprocatory device operable to actuate said mechanism, means supporting and guiding said reciprocatory device on and parallel with said standard, and a solenoid supported by and axially parallel with said standard and operable to actuate said reciprocatory device.

In testimony whereof I have hereunto set my hand in the presence of two subscribing witnesses.

CHARLES MYRON JONES.
